FIG.1

FIG. 2

INVENTOR
Milton R. Maushardt
BY
Harry Q. Schneiders

UNITED STATES PATENT OFFICE

130,745

DESIGN FOR A LIGHTING FIXTURE

Milton R. Mausshardt, Piedmont, Calif.

Application April 26, 1941, Serial No. 100,636

Term of patent 7 years

To all whom it may concern:

Be it known that I, Milton R. Mausshardt, a citizen of the United States, residing at Piedmont, in the county of Alameda and State of California, have invented a new, original, and ornamental Design for a Lighting Fixture, of which the following is a specification, reference being had to the accompanying drawing forming a part thereof.

I claim:

The ornamental design for a lighting fixture, substantially as shown.

MILTON R. MAUSSHARDT.
